CONSTANT EFFICIENCY SOUND AMPLIFIER

Samuel Rubinstein, New York, N. Y.

Application November 26, 1938, Serial No. 242,515

1 Claim. (Cl. 181—27)

This invention relates to sound amplifying devices.

One object of the invention is to provide a device of the character described according to a new and improved principle whereby the efficiency curve of the sound amplifying device is relatively constant.

The provision of a mechanical sound amplifier having a uniform efficiency curve has long been sought for, the usual curve having a peak where the frequency happens to best harmonize with the vibratory characteristics of the horn or other sound amplifier. From that peak it has been observed that the curve dropped sharply on both sides, indicating a greatly lowered efficiency. As a consequence the tones have suffered distortion, often resulting in harsh or raucous notes which would have the effect of confusing the sounds and produce noise instead of clear music. With my invention, the efficiency curve is relatively uniform, the peak referred to being flattened down and the low points of the curve being substantially raised. The result is my amplifier will reproduce notes accurately over the entire musical scale and regardless of the volume of sound produced.

Another object of the invention is to provide a simple compact and durable amplifier, capable of attaining results which cannot be obtained electrically, as in a radio receiving unit.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a perspective isometric view with parts removed and in section showing a device embodying the invention.

Fig. 2 is a horizontal sectional view of the device.

Fig. 3 is a sectional view taken on the line 3—3 of Fig. 2.

Fig. 4 is a sectional view of the device, like that of Fig. 2, but showing a modification on a reduced scale.

The advantages of the invention as here outlined are best realized when all of its features and instrumentalities are combined in one and

the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Generally described, the invention includes a relatively nonvibrating sound distributing chamber, with relatively freely vibrating boards mounted in operative relation thereto. These boards or walls are desirably restrictedly responsive to the sound impulses through openings in the chamber walls. Preferably these vibratory walls taper to accommodate different wave lengths, and desirably the walls are of different widths to accommodate different ranges of wave lengths, so that a resonator results responsive to a particular range of sound wave frequency. In conjunction with these walls, it is best to provide compartments for transmission of sound waves to the respective vibratory walls according to their individual ranges. For the very short wave lengths, the speaker unit or sound source preferably directly communicate with the vibratory walls at their narrowest regions.

Referring in detail to the drawing, 10 denotes the invention. The same may include a chamber 11 formed by side walls 12, 13 and an end wall 14. All of these walls consist of a material or are so constructed as to be relatively unresponsive to sound waves. The chamber 11 is relatively closed except for the end opening 15 and the lateral openings such as 16, whereby the chamber 11 constitutes a sound conduit or distributing chamber. Regarded as such, it will be apparent that the chamber 11 may be made of any suitable size and shape, for example, it may be arranged to taper toward the end opening 15.

Responsive to the sound waves from the chamber 11 are one or more compartments or elements such as the vibratable boards or walls 17, 18. Desirably the same may be tapered with their narrower end portions adjacent to the chamber 11 end opening 15. Where a plurality or a series of walls 17, 18 are used, two or more may be of substantially different widths, so that each accommodates a different range of sound waves. The walls 17, 18 may be variously mounted. For instance, bridge pieces 19 interconnect the chamber 11 with the walls, such as the walls 18 and desirably form compartments 20, 21 between the chamber and the adjoining walls 17, 18. It will be noted that the bridge pieces 19 may be in-

tegral extensions of the chamber walls 12, and that preferably, where the walls 17, 18 are marginally interconnected as at 22, the bridge pieces extend to points spaced from the corners 22. This 5 has a double purpose, since it results in that the compartments 20 are of substantially greater width than the compartments 21, and permits greater freedom of vibration of the walls 17, 18, particularly the former which are thus substantially wider than the operative parts of the walls 18.

It will be observed that the openings may increase in width downward to conform to the character of the sounding walls 17, 18. The latter may desirably be spaced from the wall 14 at their lower edges 23, the latter and the upper edges 24 being preferably free.

For supporting a sound source 25, such as a diaphragm or magnetic unit or other device, 20 in spaced relation to the chamber end opening 15, the bridge pieces 19 desirably extend above the end opening 15, and the upper end portions of the vibratory walls 17, 18 similarly extend above the end opening 15, with the unit 25 25 adapted to seat on the extensions 26 of the bridge pieces. For instance, the latter may be rabbeted as at 27 for this purpose. Thus the unit 25 may transmit its full sound strength to the chamber 11, and yet permit high frequency 30 waves to travel directly to the upper portions of the vibratory walls 17, 18. In order that the edges 28 of the opening 15 shall not impede the sound waves, these edges 28 are preferably beveled off as shown.

35 In operation, the sound waves from the sound source 25 travel straight ahead into the relatively nonvibrating second distributing chamber 11 from which they are distributed through the openings 16 to the vibratable walls or elements 17, 18 as at the open ended compartments 20, 21. The arrangement is such that the longest sound waves are transmitted to the lowest portions of vibratory elements, the progressively shorter sound waves operating at correspondingly higher, that is, narrower points of these elements. Thus the elements 19 are responsive to a range 40 of sound waves longer than at least part of the range to which the elements 18 are responsive. If desired, the elements 18 may terminate above 45 the bottom edges of the elements 17. The very short frequency notes, pass laterally above the edges 28 directly to the adjacent narrow areas of the elements 17, 18. Thus the amplifier works with equal efficiency for all sound waves, since

the amplifier has many points that conform to the different sound waves, and undesired horn and cone effects are avoided.

In Fig. 4 is shown a modification to indicate that certain parts of the device 10 may be desirably tensioned. For example, the device 30 may have walls such as 13, 17 and 18, except that walls 12a terminate at a wall 13, and bridge pieces 31 are provided in place of the adjacent elements 19. These bridge pieces 31 are securely connected to the wall 18 but are spaced from the adjacent wall 13, to permit intermediate tensioning thumb screws 32 of the right-hand, left-hand type to interconnect the elements 12a and 31. Accordingly, adjustment of the screws 15 32 may cause a tensioning or an expansion force to be exerted on the walls 17, 18 relative to the walls 12a, 13 to produce desired tonal qualities.

I claim:

A device for amplifying sound received from 20 a loud speaker unit, including a first member having side walls providing a tapered chamber, said member having an end wall connected to the side walls and forming a complete closure for the chamber at the large end thereof, a 25 second member having a tapered passage therein receiving the first member so that both members taper in the same direction, the side walls of the first member being spaced inwardly of the side walls of the second member to thus afford sound passages therebetween, the side walls of the first member having openings elongated in the direction of the taper and communicating with the last mentioned passages so that vibrations can enter the latter through said openings, 30 all the walls of the first member being constructed of a material that is adapted to absorb sound vibrations so as to be relatively incapable of being vibrated by sound vibrations, the walls of the second members being vibrationally responsive to said sound vibrations transmitted thereto through said openings, means interconnecting the members to support the second member with the ends thereof being free, the second member having at its small end a portion constituting a continuation of the first mentioned passage and aligned therewith and extending beyond the adjacent end of the first member, and a loud speaker unit mounted in said portion and facing into the first member, and the latter 45 having its adjacent end edges free and spaced inward of the said unit.

SAMUEL RUBINSTEIN.
